UNITED STATES PATENT OFFICE.

ASAHEL SMITH, OF CHATHAM, ONTARIO, CANADA.

SEED-PLANTER.

SPECIFICATION forming part of Letters Patent No. 295,297, dated March 18, 1884.

Application filed November 24, 1883. (No model.)

To all whom it may concern:

Be it known that I, ASAHEL SMITH, of Chatham, in the county of Kent, Province of Ontario and Dominion of Canada, have invented 5 a new and useful Improvement in Seed-Planters, of which the following is a full, clear, and exact description.

Reference is to be had to the accompanying drawings, forming a part of this specification, 10 in which similar letters of reference indicate corresponding parts in all the figures.

Figure 1 is a rear elevation of a seed-planter to which my improvement has been applied, parts being omitted. Fig. 2 is a plan view of 15 the seed-dropping slide and a part of a cam-wheel. Fig. 3 is a sectional rear elevation of my improvement, showing a part of the drive-wheel and a part of the seed-dropping slide. Fig. 4 is a side elevation of the flanged 20 wheel that carries the cam-wheel. Fig. 5 is a side elevation of the cam-wheel. Fig. 6 is an edge view of a part of the same. Fig. 7 is a side elevation of the wheel-holding springs. Fig. 8 is a side elevation of a modified form 25 of cam-wheel. Fig. 9 is an edge view of a part of the same.

The object of this invention is to promote accuracy in the operation of seed-planters, and also to facilitate the adjustment of the seed-dropping mechanism. 30

The invention consists in the construction and arrangement of parts, as will be herein-after described and claimed.

The cam-wheel is seated upon a flanged 35 wheel attached to the drive-wheel, where it is held in place by springs engaging with ratchet-teeth in the inner edge of the said wheel, and attached to a band placed upon the drive-wheel hub, so that the seed-dropping slide will be operated with certainty, 40 and the cam-wheel can be readily adjusted, as will be hereinafter fully described.

A represents the wheels; B, the axle; C, the seed-boxes; D, the seed-conducting spouts; 45 E, the seat-standard, and F the seat of an ordinary seed-planter.

G is the seed-dropping slide, which passes through the lower parts of the seed-boxes C, and has apertures H formed in it to receive

seed from the seed-boxes C and drop it into 50 the spouts D.

To the spokes of one of the wheels A is secured, by hook-bolts I, or other suitable means, an annular wheel, J, having a flange, K, around its outer edge, to form a seat for 55 the annular wheel L, which has serrated cams M formed upon its side to operate the seed-dropping slide G to drop the seed.

Upon the side of the annular wheel L, between the cams M, are formed lower cams, N, 60 to jar the seed-dropping slide G when its apertures H are in position to receive seed, and thus cause the seed to enter the said apertures.

Upon the inner edge of the annular cam-wheel L are formed ratchet-teeth O, with which engage the outer ends of three (more or less) springs, P, the inner ends of which are attached to a band, Q, placed upon the hub of the drive-wheel A. The springs P 70 hold the cam-wheel L to its place upon the flanged wheel J, prevent it from sliding upon the said wheel, and allow the said cam-wheel to be readily adjusted to cause the seed-dropping mechanism to drop the seed in line 75 with the cross-rows of the hills previously planted.

When the machine is to be used for planting beans or other seeds in drills, the cam-wheel L is replaced by an annular wheel, R, 80 provided with a circular row of cams, S, of uniform height, as shown in Figs. 8 and 9, the said wheel having ratchet-teeth O in its inner edge, in the same manner as the wheel L, for the springs P to engage with. 85

The seed-dropping slide G is held against the cam-wheel L by a spring, T, attached to the frame of the planter, and pressing against a pin, U, or other rest, attached to the said slide G. 90

Having thus described my invention, I claim as new and desire to secure by Letters Patent—

1. In a seed-planter, the combination, with the drive-wheel A and the spring-held seed-dropping slide G, of the flanged wheel J; the cam-wheel L, having interior ratchet-teeth, O, and the springs and band P Q, whereby the 95

said seed-dropping slide will be operated with certainty, and the cam-wheel can be readily adjusted, as set forth.

2. In a seed-planter, the cam-wheel L, provided on its inner periphery with ratchet-teeth and its inner face with serrated cams M, arranged, as shown, for operating the drop-

per-slide, and cams N between said cams M, for jarring the dropper-slide, substantially as set forth.

ASAHEL SMITH.
